BOAT

Victor Kashe, 1128 Hurley, Fort Worth, Tex.

Filed Oct. 19, 1961, Ser. No. 67,231

Term of patent 14 years

(Cl. D71—1)

FIG. 6.

FIG. 5.

FIG. 8.

I claim:

The ornamental design for a boat, substantially as shown.
